UNITED STATES PATENT OFFICE.

WILLIAM WOODRUFF ROBERTS AND LYNN T. ROBERTS, OF SHELBYVILLE, KENTUCKY.

ELECTRIC LAMP.

Application filed March 10, 1924. Serial No. 698,138.

To all whom it may concern:

Be it known that we, WILLIAM W. ROBERTS and LYNN T. ROBERTS, citizens of the United States, residing at Shelbyville, in the county of Shelby and State of Kentucky, have invented certain new and useful Improvements in Electric Lamps, of which the following is a specification.

This invention relates to electric lamps of the type employing a bulb and filament such as are commonly known as incandescent lamps.

The invention also relates to light projectors where such lamps are employed.

In the employment of light projectors such as the head lights on automobiles. It is the direct intense rays from the filament which tend to cause such intense illumination as to produce glare with its accompanying dangers. Attempts have been made to over come this by providing a screen between the filament and the eye of a person observing the lamp. Such attempts have revolved themselves into two classes; in one of which the outer or front end of the lamp is frosted, made from opalescent glass or in some other manner made translucent instead of transparent. In the other methods, an opaque screen has been employed. By the use of the first method much light is wasted, being absorbed by the construction of the lamp employed and in the second method not only is light wasted but a shadow is thrown by the opaque screen.

One important object of the present invention is to provide an improved construction of lamp of this type especially adapted for use in connection with automobile headlights and the like and which is of such nature as to eliminate direct observation of the filament while at the same time utilizing as much of the light as could be utilized with an ordinary clear glass lamp and without a screen.

A second important object of the invention is to provide an improved lamp of this character wherein the injurious effects of shadow will be eliminated.

A third important object of the invention is to provide an improved combination of parabolic reflector with the improved lamp in such manner that certain of the rays from the filament will, after double reflection, be projected in a straight parallel beam or pencil. Other rays, after single reflection, will be projected to intersect each other and then

spread in a cone, while still other rays, without reflection, will spread out to illuminate the sides of the road.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a transverse section through a headlight showing the improved lamp in position and indicating by dotted lines the course of the light rays.

Figure 2 is a greatly enlarged side elevation, partly in section, through the improved lamp showing its construction.

In the present disclosure the lamp is shown as having an ordinary oval bulb 10 provided with the usual metallic neck 11. This bulb also has the usual filament 12 disposed centrally of the greatest transverse diameter of the lamp. The bulb is made of the usual clear glass but on the exterior of its outer or forward end it is provided with a coating 13 of silver which is covered and protected by an opaque coating 14. The silver coating 13 is terminated rearwardly in forwardly spaced relation to the plane perpendicular to the axis of the lamp and passing through the filament and bulb at the greatest diameter of the latter. It is preferred that the silver coating cover about one-sixth of the surface of the bulb, though it may cover somewhat more than this.

With this construction the silver coating acts as a reflector and constitutes a concave mirror confronting the filament 12. When such a lamp as this is placed in the usual manner in a headlight 15 provided with a parabolic reflector 16 and is so arranged that the mirror 13 is in alignment with and in front of the focus of the reflector 16, and the filament 12 also in front of the reflector focus, then, under these circumstances, certain light rays as 17 emanating from the filament 12 will strike the mirror 13, be reflected through the reflector focus to the reflector 16 and there be a second time reflected to pass forwardly in substantially parallel relation. Others of these rays, as the rays 18, will pass directly from the filament to the reflector 16 and be reflected in con-

verging relation to a point 19 and thence in diverging relation as shown. None of the rays from the filament will pass directly forward, but the opaque mirror coating will 5 not appear to cast a shadow because the rays 18 meeting at the point 19 will greatly reduce and practically destroy all shadow effect. Finally, by proper proportioning the mirror, certain rays 20 will pass from the 10 filament 12 without striking the reflector of the lamp in diverging relation and thus illuminate the sides of the roads. It is, of course, to be understood that the filament and mirror are in proper relation to each 15 other to accomplish this result.

By the use of this arrangement it is found that a headlight gives more light with the same voltage than with any other lamp of corresponding candle power, the 20 field of blindness is reduced to a greater degree than with any other bulb of smooth clear glass lens and it can be used in the headlight without producing any blinding effects, and no dark spot or shadow is cast.

25 There has thus been provided a simple and efficient device of the kind described and for the purpose specified.

Having thus described the invention, what is claimed as new, is:

The combination with a headlight having 30 a housing and a main parabolic reflector mounted therein and facing the forward end of the housing and terminating forwardly closely adjacent said end; of a lamp socket projecting through the rear end of the reflector in the axis thereof, of an incandescent lamp bulb mounted in said socket and having its filament close to but in front of the focus of the reflector, said bulb being coated on its forward end with a reflecting surface and a protecting coating on said surface, whereby rays of light from the lamp filament directed on the parabolic reflector issue in a converging beam, while rays of light directed against the reflecting surface 45 on the bulb are reflected to the parabolic reflector and redirected by the latter in a parallel beam of light forward of the headlight housing.

In testimony whereof we affix our signatures.

WILLIAM WOODRUFF ROBERTS.
LYNN T. ROBERTS.
